DESIGN FOR A MOUTHPIECE FOR SMOKING PIPES, CIGARETTE HOLDERS, OR SIMI- LAR ARTICLES

Rudolph Hirsch, North Bergen, N. J., assignor to
The Reiss-Premier Corporation, West New York, N. J., a corporation of New Jersey

Application August 16, 1939, Serial No. 86,728

Term of patent 14 years

To all whom it may concern:

Be it known that I, Rudolph Hirsch, a citizen of the United States of America, residing in North Bergen, Hudson County, New Jersey, have invented a new, original, and ornamental Design for a Mouthpiece for Smoking Pipes, Cigarette Holders, or Similar Articles, of which the following is a specification, reference being had to the accompanying drawing, forming part thereof.

In the drawing:

Figure 1 is a side elevation of a mouthpiece for smoking pipes, cigarette holders, or similar articles showing my new design;

The design is characterized by a mouthpiece of the configuration shown having at the bit end thereof an enlargement of the specific form illustrated.

I claim:

The ornamental design for a mouthpiece for smoking pipes, cigarette holders, or similar articles, substantially as shown and described.

RUDOLPH HIRSCH.
